Fig. 4.

FIGURE 1 is a front perspective view of a combined filing cabinet and drafting table showing our new design; the cabinet top being shown in cabinet closing position, and the instrument drawer thereof in closed position;

FIGURE 2 is a rear perspective view thereof;

FIGURE 3 corresponds to FIGURE 1 but shows the top of the device opened to drafting position, and the instrument drawer out in open position; and

FIGURE 4 corresponds to FIGURE 2 but shows the top in fully opened position for access to the interior of the cabinet.

The appearance of the combined filing cabinet and drafting table of our design is substantially the same as viewed from either side thereof.

We claim:

The ornamental design for a combined filing cabinet and drafting table, substantially as shown and described.
